CLAIM

The ornamental design for a display screen or portion thereof with transitional keyboard graphical user interface, as shown and described.

DESCRIPTION

FIG. 1 is a front view of a first image of a display screen or portion thereof with transitional keyboard graphical user interface showing my new design;

FIG. 2 is a front view of a second image thereof;

FIG. 3 is a front view of a third image thereof; and,

FIG. 4 is a front view of a fourth image thereof.

The appearance of the transitional image sequentially transitions between the images shown in FIGS. 1 through 4. The process or period in which one image transitions to another image forms no part of the claimed design. The outermost dot-dot-dash broken line showing of a display screen or portion thereof, as well as the broken line showing of elements of the graphical user interface, illustrate portions of the article and do not form part of the claimed design.

Each of the images would also represent what a user will see when he/she wears a virtual reality device.

1 Claim, 4 Drawing Sheets
